US00D808568S

(12) **United States Design Patent** (10) **Patent No.:** **US D808,568 S**
Chang et al. (45) **Date of Patent:** **** Jan. 23, 2018**

(54) **LIGHTING FIXTURE**

- (71) Applicant: **Atlas Lighting Products, Inc.**,
Burlington, NC (US)
- (72) Inventors: **Cheng S. Chang**, Elon, NC (US); **Scott T. Ellingson**, Graham, NC (US); **James H. Bennett**, Greensboro, NC (US); **R. Samuel Hunt, III**, Burlington, NC (US)
- (73) Assignee: **Atlas Lighting Products, Inc.**,
Burlington, NC (US)
- (**) Term: **15 Years**
- (21) Appl. No.: **29/576,390**
- (22) Filed: **Sep. 2, 2016**
- (51) LOC (11) Cl. **26-03**
- (52) U.S. Cl. **D26/85**
- (58) **Field of Classification Search**
USPC D26/72, 85, 87, 92; D10/106.6, 106.8

(57) **CLAIM**

The ornamental design for a lighting fixture, as shown and described.

DESCRIPTION

FIG. 1 is a front top left perspective view of a first embodiment of our new design;

FIG. 2 is a front bottom left perspective view thereof;

FIG. 3 is a top view thereof;

FIG. 4 is a bottom view thereof;

FIG. 5 is a front view thereof;

FIG. 6 is a rear view thereof; and

FIG. 7 is a right side view thereof, the left side view being a mirror image thereof.

FIG. 8 is a front top left perspective view of a second embodiment of our new design;

FIG. 9 is a front bottom right perspective view thereof;

FIG. 10 is a top view thereof;

FIG. 11 is a bottom view thereof;

FIG. 12 is a front view thereof;

FIG. 13 is a rear view thereof; and,

FIG. 14 is a right side view thereof, the left side view being a mirror image thereof.

The views of the lighting fixture not shown form no part of the claimed design. The dashed lines in the Figures refer to optional features that form no part of the claimed design.

1 Claim, 14 Drawing Sheets
